UNITED STATES PATENT OFFICE.

ROY L. BADGER, OF YOUNGSTOWN, OHIO.

LOW-WATER ALARM.

Application filed February 10, 1926. Serial No. 87,202.

The object of this invention is to provide a reliable low water alarm adapted to indicate certainly and promptly the fact that the water level in the boiler has descended to a dangerous point. My alarm is especially well suited for locomotive boilers and has been developed particularly to enable certainty of operation, notwithstanding the sudden changes in water level due to the rolling, tipping and plunging of the locomotive on the track and the irregularities consequent upon grades, sudden stops and extreme demand put on the boiler in starting heavy trains.

It has been customary to locate the temperature controlling element in most water alarms in a region just above the lowest safe level of the water, so that such element will be subjected to steam action when the water descends to a danger point. My observations and experiments have indicated that there is immediately above the water a more or less definite layer of heavy wet saturated steam, which has considerable capacity for conducting heat, and I have found that I can produce much more accurate results by arranging the device so that the heat about the temperature responsive element is concentrated in a region which is not only above the permissible low water level, but is above the layer of wet saturated steam when the water is at such low level. Accordingly my invention includes a temperature responsive element to control the alarm operation and means for transmitting heat to such element from the fire box so arranged as to concentrate the heat in a region which is above the layer of heavy saturated steam which will lie over the water when the water has dropped to a dangerous level.

My invention includes not only the above described characteristic of location of the concentrated heat region, but the peculiar means hereinafter described whereby I accomplish such location for concentration of heat and cause the alarm to remain in operation until the water has descended to the dangerous level and to thereupon operate with promptness and certainty. My invention also includes the particular embodiment of these features illustrated in the drawing which enables convenient installation and adjustment to meet conditions which vary with different locomotives.

I prefer to use as the pressure controlling element a thermo-couple mounted in a suit-

able casing which is installed in a recess in the heat transmitting plug in the region of heat concentration. The means for positioning such device, and allowing its ready removal for inspection, are also comprised within my invention.

My invention is hereinafter described in connection with the embodiment illustrated in the drawings, while the essential novel features are summarized in the claims.

In the drawings, Fig. 1 is a side elevation of a portion of a locomotive equipped with my low water alarm; Fig. 2 is vertical section through the low water alarm, part of the construction being broken away intermediately; Fig. 3 is a horizontal section through the heat transmitting plug, as indicated by the line 3-3 on Fig. 2 looking upwardly; Fig. 4 is a cross-section of the device in the region of the thermo-couple; Fig. 5 is a fragmentary detail, on an enlarged scale illustrating the threaded engagement of the plug and shell.

As shown in Figs. 1 and 2 of the drawings, 80 10 indicates the crown sheet and 11 the roof sheet of a locomotive boiler, and 12 a standard gauge glass in communication with the water and steam spaces between such sheets. The casing or external member of my alarm 85 includes a tube 20 which extends through the roof sheet to a point adjacent the crown sheet and it is tightly connected with a bushing 21 screwing into the crown sheet. A suitable stuffing box carried by the roof sheet 90 and surrounding the tube clamps it tightly thereto.

As shown, the tube 20 is externally threaded near its lower end and screws into an internally threaded recess in the bushing 21, 95 thereafter the tube and bushing are welded together, preferably by the application of metal from arc welding, as indicated by the fillet 24, thus securing these parts permanently together. The bushing has tapered 100 external threads 25 by which it may make a tight connection with the crown sheet. The lower end of the bushing is provided with notches 26, enabling it to be turned by a spanner wrench.

The stuffing box referred to carried by the roof sheet, comprises a bushing 30 having a tapered thread engaging the roof sheet, an internally flanged nut 31 screwing onto the bushing and packing 32 between the nut 110 and an inclined shoulder in the bushing. The opening of the roof sheet which the

bushing occupies is of a larger diameter than the exterior diameter of the bushing 21. This enables the bushing 21 to be permanently secured to the tube 20 before the same is installed then the tube with its bushing to be passed through the opening of the roof sheet into registration with the opening of the crown sheet; then the application of a spanner wrench to the notches 26 to turn the parts into place without subjecting the connection between the tube and bushing 21 to strain. After the tube is thus mounted in the crown sheet, the bushing 30 is applied to the roof sheet and the packing completes this portion of the installation.

It will be observed that the interior of the tube 20 has a continuous thread 22 extending from the lower end to a considerable height in the tube. This thread adjustably carries a large copper plug 40 which stands within the tube 20 and for the most part is free from it but has an enlarged zone 41 externally threaded to engage the internal threads 22 near their upper region. The region of the threaded engagement of the plug with the tube is so located that it will be substantially at the bottom of the dry steam when the water level is at the bottom of the gauge glass.

The lower end of the plug 40 is preferably made angular so that it may be readily turned by a wrench to thus adjust it up or down the tube. The drawing illustrates this inner end of the plug square. Such portion is preferably encased by some material tougher than copper, as, for instance, cast iron. Such casing, which may be readily cast about the copper core and is illustrated at 43 by the different section lining in Figures 2 and 3, protects the head from the fire box gases and from damage by the wrench.

The copper plug 40 has in its upper portion a recess 45 leading downwardly from the upper end. This recess is occupied by the active portion of the thermo-couple. This thermo-couple may be of any standard form and it is encased in a suitable tubular member or bulb 50 which occupies the recess 45 and above that in a tube 51 leading to the exterior. The thermo-couple casing 50 has a head 52 with a conical under face which rests on a conical seat 47 in the plug. Above this seat the plug is internally threaded. Into these threads I screw a tube 60 which leads to the exterior of the device and is provided with notches 61 for the application of a spanner wrench to turn the tube. The tube thus acts as a nut to clamp the thermo-couple casing in place in the plug. The tube 60 is properly located near its upper end by a flange collar 70 surrounding the tube 60 and screwing onto the upper end of the tube 20. One or more vents 28 are made through the tube 20 between the stuffing box nut 31 of the collar 70.

The thermo-couple within the casing 50 forms a portion of an electric circuit which may lead by suitable conductors 80 and 81 (Fig. 1) to an indicator in the nature of a voltmeter 82 located at some suitable point. The needle 83 of this indicator may be one terminal of a local circuit 84 leading therefrom through a bell 85 and a battery 86 to another terminal 87 adapted to be engaged by the needle. Accordingly, when the thermo-couple is sufficiently heated, the needle 83 swings over to make a contact with the terminal 87, resulting in the ringing of the bell. These electro-magnetic elements however, are to be taken as a conventional illustration of any suitable indicator or alarm operated by the device within the casing 50.

Attention is called to the looseness of the threading of the plug into the shell, as indicated in an exaggerated manner in Figs. 2 and 5. These figures illustrate the relative position of the threads when the structure is cold. In normal operation, however, the expansion of the plug causes this threading engagement to become tight. This peculiar thread engagement is an important feature of the invention as hereinafter explained in connection with the description of the operation.

It will be noticed from Fig. 2, that the region of engagement of the plug and shell while within the normal water space is a very material distance above the safe low water level. This safe low water level corresponds with the level of the bottom of the gauge glass, and the region of threaded engagement is preferably several inches above this level, about three or four inches above it being found most satisfactory. This is on account of the following operative characteristics.

Due to the rapid ebullition of steam in a locomotive boiler, the irregular demand for such steam and the rocking and plunging of the boiler, the layer of saturated steam immediately above the water, contains so much water in suspension that it is a fair conductor of heat and may result in conducting away the heat from region of the alarm control intended to be hot, when such region is located, as ordinarily, just above the safe low water level, and thus prevent the operation of the alarm until the water level has dropped materially below the safe limit, with the possibility that it may uncover the crown sheet before the alarm is given.

I have found that although the water level varies greatly in operation of the locomotive, the layer of heavy saturated heat-conducting steam is of approximately constant thickness on top of the water, and accordingly by locating the controlling region of the device with reference to the top surface of the layer of heavy saturated steam,

I obtain a much more accurate result than where it is spaced with reference to the theoretic safe low water level.

As stated, when the device is installed the 5 threads 41 on the plug seat the threads 22 in the tube comparatively loosely. Now, when the boiler is heated to normal, the copper plug extending into the fire box conducts heat from the fire box to the region 10 of these engaged threads, and the expansion of the plug causes the engagement to become tight. This allows the heat to pass from the plug to the tube, and the water or heavy 15 saturated steam about this region of the tube conducts away the heat so that the pyrometer bulb is not heated to the operating point.

Now, as soon as the water level drops to the bottom of the gauge glass, which is regarded as the danger line, the surmounting 20 layer of heavy saturated steam has dropped below the region of threaded engagement of the plug and shell; then the dry steam is not able to conduct away the heat from the tube, and the body of the tube (which is 25 comparatively thin and has a much less cross-sectional area than the copper plug) is insufficient to conduct heat away from the plug, and accordingly the heat of the latter becomes localized about the pyrometer bulb 30 and increases in that region. At the same time, heat is transmitted by the tight threads to the adjacent portion of the shell, which latter expands in this region, loosening the threads, and such loosening interferes with 35 the transmission of heat from the plug to the shell. Thus there is a state of thermal equilibrium, where the shell is maintained out of tight contact with the plug, by such heat as is transmitted and cannot be conducted 40 away, while the plug not being able to dissipate its heat rapidly accumulates heat in this zone, with the result that the pyrometer bulb is heated to the operating point.

Attention is called to the vent from the 45 upper portion of the tube outside of the boiler. This relieves any air pressure which might result within the tube, when only dry steam is around the critical region; the loosening of the threads may allow the upward 50 passage of heated air from below the threads of the plug, and, if so, the same further serves in maintaining the heat within the tube and about the upper portion of the plug above the threaded region.

55 The net result of the peculiar means of suspending the copper plug and the relative location of such suspension, as above described, is that in normal operation the alarm actuator is maintained at a temperature below that which will operate the alarm, but as soon as the water level has dropped to the danger region the rising temperature at the critical region occurs with great rapidity, insuring an almost immediate operation 60 of the alarm. In tests I have made, under

all sorts of operating conditions of the locomotive, where the parts were properly set, the alarm did not operate so long as water was visible in the gauge glass, but when the water was allowed to descend below that 70 level the alarm invariably operated in less than one minute after the water disappeared from the glass.

By reason of the threaded engagement of the plug with the tube, the critical region 75 may be varied in height as desired by simply rotating the plug by the application of a wrench to the lower end. I provide suitable means to prevent the plug unscrewing from the jar of operation when the threads are 80 loose. As shown, this comprises a set screw 75 passing through the tube 20 outside of the boiler and engaging this tube 60, which is screwed tightly into the plug. The parallel thread engagement of the plug enables 85 adjustment not only for different types of locomotives, but for different conditions of operation. The construction of my device is simple; it may be cheaply manufactured; may be readily installed, and is likewise 90 readily removable for inspection.

Having thus described my invention, I claim:—

1. The combination, with a boiler, of a metal tubular shell extending upwardly 95 from one wall of the boiler into the normal water space and beyond the safe low water level, a heat conducting plug within the shell secured to the shell in a region which is above the layer of heat-conducting saturated 100 steam which overlies the water when the latter has descended to an unsafe level, and an alarm controlled by concentration of heat in said region.

2. The combination with a boiler having 105 a crown sheet, of a metal tubular shell secured at its lower end to the crown sheet and open to the fire box, a heat conducting plug within the shell extending into the fire box and secured adjacent its upper end to the 110 shell in a region which is above the layer of heavy heat-conducting saturated steam which overlies the water when the latter has descended to an unsafe level, an alarm, and means for actuating it controlled by concentration of heat in the upper portion of the plug.

3. The combination with a locomotive boiler, having a crown sheet and roof sheet, 115 of a metal tubular shell extending from one to the other and open to the fire box and to the atmosphere, a heat conducting plug within the shell secured to the shell in a region which is above the layer of heavy heat-conducting saturated steam which overlies the water when the latter has descended to an unsafe level, said plug being spaced 120 from the shell below such region, and an alarm actuatable by the heat in the plug at such region.

4. The combination with a boiler equipped with the usual gauge glass, of a tubular conduit connected to the crown sheet, a heat transmitting plug within the conduit and connected with it in a region which is in the dry steam as soon as the water level has descended below the gauge glass, and means whereby the heat in the plug in the region of such connection may effect the operation of an alarm.

5. The combination with a boiler, of a tubular shell connected to the crown sheet, a heat transmitting plug within the shell extending materially above the safe low water level, there being a threaded connection between the plug and shell in a region which is in the dry steam as soon as the water level has descended below the gauge glass, and means whereby the heat in the plug in the region of such connection may effect the operation of an alarm.

6. The combination with a boiler, of a tubular conduit leading from the fire box thereof into the water space and adapted to be partially uncovered as soon as the water level has descended to the danger level, and a heat conducting plug within the shell and spaced from it, from the fire box to the region adapted to be uncovered, said plug and shell having a threaded engagement above the layer of wet saturated steam which overlies the water at said low level, said threaded engagement being arranged to become loose when the region of engagement is in the dry steam, and means whereby the excessive heat of the plug in the region of the threads may operate an alarm.

7. The combination with a boiler, of a tubular conduit leading from the fire box thereof into the water space and adapted to be partially uncovered when the water level descends to the danger level, and a heat-conducting plug within the shell, and spaced therefrom from the fire box to the region adapted to be uncovered, said plug having an externally threaded engagement engaging internal threads in the conduit above such region, such engagement being loose when the parts are cold, and means whereby the excessive heat of the plug in the region of the threads may operate an alarm.

8. In a low water alarm, the combination with a boiler, of a metal shell in the water space and connected with the fire box, said shell having an internal thread, a heat conducting plug within the shell and having a threaded engagement with it above the safe low water level, and a thermo-couple seated in the upper end of the plug and operated by excessive heat in the threaded region.

9. The combination with a boiler, of a metal tube connected with a crown sheet and in communication with the fire box space, a copper plug within such tube and having a threaded connection with it in a region above

the layer of wet saturated steam which overlies the water at a safe low water level, said plug being out of contact with the tube beneath its region of connection, the cross sectional area of the plug within the tube being materially greater than the cross-sectional annular area of the tube itself, and means whereby excessive heat in the plug in the region of its connection with the shell may operate an alarm.

10. In a low water alarm, the combination with a boiler, of a conduit connected with the crown sheet and communicating with the heating chamber, a heat-conducting plug within the conduit having an externally threaded portion engaging an internal thread in the shell, a cavity in the upper portion of the plug leading downwardly to the region within the threaded portion, a thermo-couple within such cavity, and an alarm adapted to be actuated by the thermo-couple.

11. In combination with a boiler having a crown sheet and a roof sheet, a metal shell extending from one sheet to the other and threaded into the crown sheet, a stuffing box carried by the roof sheet surrounding the shell, a heat conducting plug within the shell connected in its upper region with the shell well above the safe low water level, there being means for obstructing radiation directly from the plug to the water below such region, there being a cavity in the upper end of the plug and a pyrometer bulb occupying the cavity.

12. In combination with a boiler having a crown sheet and a roof sheet, a metal shell extending from one sheet to the other and threaded into the crown sheet, a stuffing box carried by the roof sheet surrounding the shell, there being a passageway from the shell above the stuffing box, a heat conducting plug within the shell and extending into the fire box at its lower end connected in its upper region with the shell well above the safe low water level, there being a cavity in the upper end of the plug and a pyrometer bulb occupying the cavity.

13. In a low water alarm, the combination, with the inner and outer sheets of the boiler, of a conduit comprising a bushing threaded from the water space into the inner sheet, and a tube tightly connected with the bushing and extending out through the outer sheet, said tube being threaded from its inner end for a considerable distance, and a heat conducting plug having an enlarged externally threaded portion a considerable distance above its lower end, said externally threaded portion engaging the threads of the tube, and means affected by an accumulation of heat in the threaded region of the plug for operating an alarm.

14. The combination with a boiler, of a tube extending from the outer sheet to the inner sheet, a heat conducting plug within

- the tube connected with it in a region above the safe low water level, there being a cavity in the upper portion of the plug, a pyrometer bulb in said cavity, and a tube screwing 5 into the upper end of the plug and serving to clamp the pyrometer bulb in place, said tube extending outside of the boiler. 40
15. The combination of a boiler having a crown and roof sheet, a tubular casing extending through the roof sheet and secured to the crown sheet and having its interior in communication with the fire box space, a stuffing box carried by the roof sheet and embracing the casing, a collar on the upper 15 end of the tube, a plug occupying the casing, there being a cavity in the upper portion of the plug, a pyrometer bulb occupying the cavity, a tube extending through the collar and screw threaded into the upper end of 20 the plug and adapted to hold the pyrometer bulb in place, and an operating connection from the pyrometer bulb extending outwardly through such tube to the exterior of the boiler. 45
25. 16. The combination of a boiler having a crown and roof sheet, a tubular casing extending through the roof sheet and secured to the crown sheet and having its interior in communication with the fire box space, a stuffing box carried by the roof sheet and embracing the casing, a plug occupying the 25 casing and extending down into the fire box, said plug having an elevated enlargement externally threaded and engaging internal threads in the casing which are adapted to become loose when the threaded region is 50 surrounded by dry steam, means to prevent the plug inadvertently unscrewing when the threads are loose, and an external alarm operated by excessive heat in the threaded region of the plug. 55
- In testimony whereof, I hereunto affix my signature.

R. L. BADGER.
